UNITED STATES PATENT OFFICE.

BENJAMIN S. ATWOOD, OF SOUTH ABINGTON STATION, MASSACHUSETTS.

SHIPPING-CASE FOR JARS AND BOTTLES.

SPECIFICATION forming part of Letters Patent No. 254,899, dated March 14, 1882.

Application filed July 30, 1881. (Model.)

To all whom it may concern:

Be it known that I, BENJAMIN S. ATWOOD, a citizen of the United States, residing at South Abington Station, in the county of Plymouth and State of Massachusetts, have invented certain new and useful Improvements in Shipping-Cases for Jars and Bottles; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The present invention relates to that class of packing-boxes or shipping-cases having racks or cells for receiving and retaining bottles, jars, or other objects.

The object of the invention is to simplify the 20 construction of the box, so as to better adapt it for retaining the strips or bars constituting the rack and permit the latter to be easily removed for cleaning the box.

Another object is to strengthen the ends of 25 the box and render the same air-tight by locating a covering-piece on the inside of the customary hand-holes or openings.

To these ends the invention consists in the construction and combination of parts, which 30 will hereinafter be more fully described, and then set forth in the claims.

In the drawings, Figure 1 is a longitudinal section of a packing-box embodying my improvements. Fig. 2 is a transverse section of the same. Fig. 3 is an end elevation representing the hand-hole closed at its inner side. Fig. 4 is a detail top view of the end of the box.

The sides of the box are preferably constructed 40 of a bottom board, A, and a thinner top board, B, so as to cause said bottom board to project beyond the upper one at the inside of the box, as is clearly shown in the drawings. Vertical grooves or gains *a* are cut in the face 45 of the projecting portion of the bottom board for receiving the ends of cross-strips C, which, in connection with the longitudinal strips D, let into the same, constitute a rack or a series of cells.

50 The sides of the box, instead of being made of two boards, may each be formed of a single board or panel, which is cut so as to have its

bottom thicker than its top portion for the above-mentioned object.

The heads or ends of the box are constructed 55 of an outside board, E, an interior board, F, and vertical pieces G at the sides of the latter. The outside board, E, is generally cut so as to form a projecting portion, H, on its inner side, in which are cut the vertical grooves 60 *d* for receiving the ends of the longitudinal strips D. The interior board, F, rests upon the ledge formed by the projecting portion H of the board E, and the vertical pieces G, located at the sides of the board F, extend from 65 the top to the bottom of the box, and its inner surface is flush with the surface of the board F.

The vertical pieces are cut so as to have the grain of the wood run crosswise or contrary to the grain of the boards E F, and in this way 70 I attain increased strength at the ends of the box. A hand-hole, K, cut in each end board, E, has its edges beveled or rounded off, and at the top edge of said hand-hole the board E is cut out or reduced in thickness, so as to permit the fingers of the person to enter the space or recess formed between said end board and the inside or covering board, F. The latter is hollowed out or provided with a cavity, I, opposite the opening in the inner board, E, the 80 upper portion of said cavity being the deepest, so as to afford space for the introduction of the hand.

It will be manifest that the ends of the box are perfectly air-tight, or, in other words, air 85 cannot pass through the hand-holes, and for this reason the contents of the box are kept warmer in winter and cooler in summer, the consumption of ice being also less than if the ends were left open. The main object of having the interior bottom portion of the sides and ends of the box project beyond the upper portion thereof is to enable the grooves or gains for the rack to be cut in said projecting portion, this location of the grooves permitting 90 the strips forming said rack to be easily inserted and removed. Hence the box can be cleaned with greater facility than boxes provided with racks secured in the ordinary way.

The cover J of the box is secured or locked 100 by any approved fastening device.

Having thus described my invention, what I claim as new, and desire to secure by Letters Patent, is—

1. A packing-box or shipping-case having the lower interior portion of its sides and ends projecting inwardly beyond said upper portion and provided with vertical grooves, in combination with the strips of the rack, detachably fitted in said grooves, substantially as herein set forth.
2. The box-head having a hand-hole, and an interior covering-board provided with a cavity located opposite said hand-hole, as and for the purpose set forth.
3. In a packing-box, the combination of the

end heads, consisting of an outside apertured board, two vertical strips or bars, and a smaller interior board having a cavity, with the side boards, the cover, and the rack let into the side boards and end heads, as and for the purpose set forth. 15

In testimony whereof I affix my signature in presence of two witnesses.

B. S. ATWOOD.
